UNITED STATES PATENT OFFICE.

EDWARD ROSCOE, OF EDENDALE, AUCKLAND, NEW ZEALAND.

APPARATUS FOR DISPLAYING INFORMATION, ADVERTISEMENTS, AND THE LIKE.

Application filed June 6, 1924. Serial No. 718,370.

This invention relates to means employed for automatically displaying information, advertisements and the like, such as for showing the names of stopping places in 5 tram cars, and for displaying advertisements in shop windows or other places.

This invention provides an improved construction of a device of the above mentioned class, and comprises rollers from one to the 10 other of which, a band carrying matter to be displayed is passed behind a sight opening in a casing, in order that only a portion of said matter can be viewed at one time.

The rollers are geared together and one 15 of said rollers has fixed on its spindle a disc from which a number of pins project, said pins being adapted to be engaged by one of a pair of push pawls pivoted on the lower end of a rod, which is adapted to be raised 20 or drawn upward through guides by the action of a solenoid, on the latter being energized, and is returned or moved downwards under the action of a spring, when the solenoid is de-energized. The upper end 25 of the said rod to which the push pawls are pivoted, forms the core of the solenoid.

A screw threaded spindle geared to turn 30 at the same time as the rollers, has stops fixed thereon, between which a lever works along said screw threaded spindle, said lever having a projecting pin or arm which passes between the push pawls. On the lever reaching the end of its movement in either 35 direction along the screw threaded spindle, it strikes a stop and makes a partial turning movement, whereby its pin or arm puts the pawl at the time in use out of action, and causes the other pawl to come into use 40 in order to bring about reverse turning movement of the rollers.

The solenoid is adapted to be momentarily energized, each time a change of matter viewed through the sight opening is desired, and remains de-energized for the length of 45 time it is desired the matter shall be on view.

Hand operated means are also provided for causing turning movement of the rollers and for altering the positions of the pawls.

The band carrying the matter to be displayed is preferably formed in a number of 50 short sections or lengths each of which is adapted to carry the matter to be displayed at any one time, in order that any desired matter can be removed from said band or 55 additional matter inserted therein as and when desired.

In the accompanying drawing, in conjunction with which the invention will be further described:—

Figure 1 is a front elevation, and

Figure 2 a part end elevation of the improved device with the casing in both cases shown in section.

Figure 3 is a detail view of the operating pawls in their raised position, and

Figure 4 is a detail in perspective of the means employed for joining together the short sections of the band carrying the matter to be displayed.

The casing 1 is provided with a suitable sight opening 2 and has mounted therein rollers 3 around which passes a band 4 preferably formed of a number of short sections or lengths 4^a on each of which is placed such matter or advertisements as it is desired should be displayed at one time through the sight opening 2, the band 4 being adapted to be passed behind the said sight opening, so that only one section or portion of the band is visible at any one time.

The roller spindles 3^a are mounted in bearings attached to the casing and are geared together by means of sprocket wheels 5 keyed on the spindles 3^a and a sprocket chain 6 passed around the said sprocket wheels 5, to cause both the spindles 3^a to revolve in the same direction. A further sprocket wheel 6^a is keyed on a spindle 7 and is adapted to be driven by the sprocket chain 6, said spindle 7 being screw threaded for a portion of its length, and provided with stops 8 placed the required distance apart. The stops 8 are formed preferably by locking nuts on the spindle 7 the latter being supported by suitable bearings attached to the casing.

One of the roller spindles 3^a is extended through one of its bearings and has keyed thereon a disc 9 from which project pins 10 adapted to be engaged by push pawls 11 pivotally connected at one end of a rod 12, and working in a slotted guide 12^a attached to the casing. The other end of the rod 12 is preferably increased in diameter to form the movable core 13 of a solenoid 14.

The pawls 11 are formed by the extremities of a U-shaped member pivoted to the rod 12 at the junction of said extremities, and are arranged one at each side of the centre of the disc 9 with the projecting pins 10, so that either one of said pawls 11 can be brought into use, one to turn the spindle

3^a in one direction, and the other to turn said spindle in the reverse direction.

Threaded on the screw threaded portion of the spindle 7 of the sprocket wheel 6^a, is 5 a lever 17 having a pin or arm 18 projecting between the pawls 11 which engage the projecting pins 10 on the disc 9, on one of the roller spindles 3^a.

The upper end 17^a of the lever 17 is tapered and rounded off and has bearing against same a flat spring 19 formed with a downwardly bent portion 19^a (Figure 3).

A further flat spring 20 with an upwardly bent portion 20^a bears on and between 15 the pins 10 projecting from the disc 9 on the roller spindle 3^a, before mentioned, so as to check and hold the rollers 3 against turning in until such time as a change of matter being displayed is required, said spring 20 not 20 being strong enough to interfere with movement of the band 4 when such change is being made.

A spring 21 is provided on the rod 12 between a collar 21^a thereon and a bracket 22 25 which serves as a guide for the rod 12, when the latter is moved by the attraction of the solenoid 14.

Means, such as screws 23, are also provided for adjusting the pressures of the 30 spring 19.

The solenoid 14 is energized by any desired and usual manual or automatic circuit make and break device, (not shown as it can be wholly conventional) every time it is desired to change the matter appearing in the 35 sight opening 2. Each time the solenoid is energized, its movable core, in the present case, the upper end 13 of the rod 12, is drawn upwards against the action of the spring 21, and thereby raises the pawls 11 to the position 40 shown in Figure 3 of the drawing.

On the solenoid being de-energized, the 45 spring 21 expands and forces the rod 12 downwards, causing the pawl 11 which is for the time being in operation, to strike a pin 10 and impart turning movement to the spindle 3^a and rollers 3.

This continues to happen each time the 50 solenoid is energized, until the lever 17 screwed on the spindle 7 is worked along to and locked against one of the stops 8, where upon on the following turning movement of the spindle 7, the lever 17 is thrown over to one side and its pin or arm 18 strikes and

forces the pawl 11 then in operation clear of the pin 10 on the disc 9, which action brings into operation the other pawl 11, so that on the next upward movement of the rod 12, the reverse turning movement will be imparted to the rollers 3, the turning of the rollers being reversed each time the lever 17 locks against a stop 8.

The spring 19 acting on the end 17^a of the lever 17 presses against a side of the tapered end and holds the lever in position until the next change is desired. A hand lever 24 projects from the lever 17 through a slot in the casing 1, in order that the position of the said lever 17 can be normally reversed when desired independently of the screw 70 threaded spindle 7.

The upper end of the solenoid core 13 is preferably extended beyond the solenoid 14 and thence through the top of the casing 1 where it is provided with a convenient handle 25 in order that the rod 12 can be raised against the action of the spring 21 by hand, when it is desired to change the matter being displayed independently of the 75 said solenoid 14.

The ends of the sections 4^a of the band 4 are formed and extended as shown in Figure 4 of the drawing, said extended portions being turned back and secured to the section 4^a to which they belong so as to form loops 26. A flat rigid strip 27 is adapted to be passed 85 through the loops 26 alternately on the ends of a pair of adjoining sections 4^a, to secure the latter together to form the complete band 4. By this means, any desired number of 90 the sections 4^a can be removed as desired, or further sections can be added to the said band as occasion arises.

I declare that what I claim and desire to protect by Letters Patent in the United 95 States of America, is:—

Apparatus for the purpose specified, comprising, a disc, pins projecting from the disc, a pair of pawls arranged, one at a time, to engage with the pins, a screw threaded spindle geared to the disc, spaced stops on the spindle, a lever threaded on the spindle between the stops, an arm on the lever extending between the pawls, and a spring acting on one end of the lever.

In testimony whereof I have signed my name to this specification.

EDWARD ROSCOE.
